UNITED STATES PATENT OFFICE.

JAMES W. PLIMPTON, OF OIL CITY, PENNSYLVANIA.

LEVEL-GLASS.

No. 860,990.

Specification of Letters Patent.

Patented July 23, 1907.

Application filed December 15, 1906. Serial No. 348,082.

To all whom it may concern:

Be it known that I, JAMES W. PLIMPTON, a citizen of the United States of America, residing at Oil City, in the county of Venango and State of Pennsylvania, have 5 invented certain new and useful Improvements in Level-Glasses, of which the following is a specification, reference being had therein to the accompanying drawing.

This invention relates to levels, and its object is to 10 provide a device of this character of simple and inexpensive construction adapted to be reversed and viewed from either side.

The invention comprises improved means for securing 15 the level glass in position, and in the construction of the glass-supporting frame to adapt it to contain liquid.

The improvement will be fully described hereinafter in connection with the accompanying drawing which forms a part of this specification, and its novel features will be defined in the appended claims.

20 In the drawing, Figure 1 is a side elevation of a level embodying the invention, and Fig. 2 is a central vertical section of the same.

The reference numeral 1 designates the wooden body portion or straight edge of the device provided with a 25 circular opening to receive the level glass and its securing means.

The glass supporting frame comprises an inner cylinder 2 surrounded by a horizontal flange 3, and an outer cylindrical shell or casing 4 externally screw-threaded 30 for the attachment of rings 5, provided with threaded flanges 6. The glass plates 7 of the device are clamped on opposite sides of the frame by the flanged rings 5. The flange 3 serves as a partition to divide the space between the cylinder 2 and casing 4 into two compartments 8 and 9 adapted to contain liquid.

The outer cylinder 4 is formed with filling openings 10 closed by screw plugs 11, and the partition 3 adjacent to the inner cylinder 2 is formed with a series of openings 12 to permit liquid to pass from one compartment to the other. The flange or partition 3 is provided with an outer row of graduations 14 within the rings 5. 40

It will be apparent that the level constructed as thus described may readily be reversed and viewed from either side. 45

The liquid compartments are supplied with liquid before the frame is inserted in place, and the removable plugs prevent leakage.

What I claim and desire to secure by Letters Patent, is:— 50

1. A level comprising a body portion or straight edge, provided with a circular opening, a frame arranged within said opening and consisting of concentric cylinders, a partition dividing the space between the cylinders into two liquid compartments, glass covers for said compartments, 55 and rings provided with threaded flanges for securing the glass covers in position.

2. A level comprising a body portion or straight edge provided with a circular opening, a frame arranged within said opening and consisting of concentric cylinders, the 60 outer one of which is screw threaded and formed with liquid inlets, a partition dividing the space between the cylinders into two compartments, glass plates serving as covers for said compartments and means for securing the glass plates in position consisting of clamping rings having threaded flanges to engage the threads of the outer cylinder. 65

In testimony whereof I affix my signature in the presence of two witnesses.

JAMES W. PLIMPTON.
